3 Claims. (Cl. 315—254)

1

This invention relates to electric discharge devices of the type employing ionizable mediums such as gases or vapors and more particularly to starting and operating devices and circuits therefor.

An object of my invention is to provide new and improved starting and operating circuits for electric discharge lamps energized from a direct current source.

Another object of my invention is to provide a new and improved operating circuit for luminous electric discharge devices or fluorescent lamps energized in series from a direct current source.

A feature of my invention is the provision of continuous voltage impulses to an auxiliary electrode in the lamps for initiating a discharge between their main electrodes, and the cessation of these impulses upon the initiation of an arc discharge within the lamps. A further feature of my invention is the use of equipotential thermionic electrodes and heating thereof by alternating current in a group of lamps which are serially connected across a direct current source. These features provide the advantages of long life and efficient operation.

My invention is of general applicability whenever it is desired to operate fluorescent lamps from a direct current supply. It has been found particularly useful in the illumination of cars on electrified railways and permits the immediate utilization of the direct current supplied to the locomotive, for instance, the traction supply at 700 volts, on the lighting circuits.

For a more complete discussion of various circuits which may be utilized in operating fluorescent lamps from a direct current supply, reference is made to my copending U. S. application No. 28,223, filed May 20, 1948. Other applications and improvements in such circuits are disclosed in my copending U. S. applications Nos. 28,224 and 28,225, filed May 20, 1948, and 33,385, 33,386, and 33,387, filed June 16, 1948. All of the above-mentioned applications are assigned to the same assignee as the present invention.

For a better understanding of my invention reference may be had to the following description taken in connection with the accompanying drawing and its scope will be pointed out in the appended claims. Fig. 1 is a diagrammatic view of a plurality of serially connected electric discharge devices and a starting and operating circuit therefor incorporating my invention. Fig. 2 is a diagrammatic view of several groups of serially connected electric discharge devices, each group being connected in parallel with the other

2

groups so that if one lamp of a group should become defective only a fraction of the total lamps will be extinguished, and a starting and operating circuit therefor incorporating my invention.

Referring to Fig. 1, I have there illustrated one embodiment of my invention as applied to a group of serially connected electric discharge devices wherein the reference numerals for device 1a and the elements associated with device 1a are extended by indices to the other serially connected devices and their corresponding elements. The electric discharge device 1a (and devices 1b, 1c), such as a fluorescent lamp, therein illustrated comprises an elongated tubular or cylindrical envelope 2a having sealed into the ends thereof thermionic filamentary electrodes 3a and 4a. Filamentary electrodes 3a and 4a may comprise a coil, preferably in the form of a coiled coil of tungsten wire activated with oxides of alkaline earth metals such as a mixture of barium and strontium oxides. The envelope 2a contains a gaseous atmosphere such as a rare gas like neon, argon, or mixtures thereof, at a pressure of a few millimeters and a small quantity of mercury which, during the operation of the lamp, has a low pressure of the order of 10 microns. The device 1a may be a low pressure positive column lamp of a fluorescent type provided with a suitable phosphor or fluorescent coating. This fluorescent coating, upon excitation by the radiation produced by an electric discharge between the electrodes, transforms a shorter wave radiation due to the discharge into longer wave radiation such as radiation within the visible range. A pair of metal cups 5a and 6a serve to intercept particles of emissive material sputtered from electrodes 3a and 4a, respectively. These cups are usually connected, either outside or inside of the lamp, to the extremities of electrodes 3a and 4a. A number of advantages result from the connections between filamentary electrodes 3a and 4a and the corresponding cups 5a and 6a, namely, utilization of cup 6a as an anode and eliminating the disintegration by ionic bombardment of filamentary electrode 4a, utilization of lamps that are usually employed with alternating current, reduction of operating voltage, doubling the life of the lamp by using successively the two filamentary electrodes, i.e., by turning the lamp around when one of the filaments becomes inoperative.

Serially connected devices 1a, 1b, and 1c are connected across a suitable direct current power supply circuit 7, 1 for supplying current there-

for. The circuit 7, 1 includes a switch 8, a resistor 9, and a capacitor 10. The circuit 7, 1 is connected to the serially connected devices 1a, 1b, and 1c. The serially connected devices 1a, 1b, and 1c are connected in parallel with the other

to through stabilizing resistances 8a, 8b, and 8c which, for example, may be iron or tungsten wire enclosed in hydrogen. A double-pole manual make-and-break switch 9 may be used to connect devices 1a, 1b, and 1c to the power supply 1, 1'. A starting and operating circuit 10, 10' is connected across the direct current supply 1, 1' and comprises an inductance 11, a switching means 12, and a resistance 13. Auxiliary electrodes 14a, 14b, and 14c mounted adjacent devices 1a, 1b, and 1c are connected to a common point 15 intermediate inductance 11 and switching means 12 through a time-delay or second switching means 16. Resistance 13 serves to regulate the value of the potential which the auxiliary electrodes 14a, 14b, and 14c assume.

Transformers 17a, 17b, and 17c comprising primary winding sections 18a, 18b, and 18c and center-tapped secondary sections 19a, 19b, and 19c, respectively, are connected in parallel across an alternating current supply 20, 20' and serve to heat filamentary electrodes 4a, 4b, and 4c, respectively. The center-tap of the secondary winding section 19c is connected through the ballasting resistance 8b to the filamentary electrode 3b of device 1b and the center-tap of the secondary winding section 19b is connected through the ballasting resistance 8a to the filamentary electrode 3a of device 1a. The center-tap of the secondary winding section 19a is connected through a coil 21 of a time-delay relay or switching means 22 to the negative terminal 7 of the direct current supply through contactor 23a of the double-pole manual make-and-break switch 9. Relay 22, whose coil 21 is in series with the discharge lamp circuit, serves to suppress or interrupt the heating current flowing through filamentary electrodes 4a, 4b, and 4c by virtue of a contactor 24 of said switching means 22 which contactor is in series relationship with one of the conductors or wires which energize the primary winding sections of heating transformers 17a, 17b, and 17c. The time-delay relay or switching means 16 comprising a coil 25 in parallel with the primary winding sections of transformers 17a, 17b, and 17c serves to connect, through a contactor 26, the point 15 to a conductor that unites at a common potential the auxiliary electrodes 14a, 14b, and 14c. A contactor 23b of the double-pole manual make-and-break switch 9 energizes the alternating current heating circuit.

The switching means 12, which serves to break the inductive starting circuit, may consist of a rotary switch which may be mounted on a shaft of a converter which may supply the alternating current for the heating transformers 17a, 17b and 17c. Such a rotary switch and converter arrangement is more fully described and illustrated in my copending application No. 28,225, filed May 20, 1948, which application is assigned to the same assignee as the present application. Switching means 12 may comprise a rotary switch employing a pair of brushes 27 and 28 which ride on a metal ring 29 comprising an insulating circular section 30.

The circuit and devices indicated in Fig. 1 operate as follows: In the rest position contactor 24 is closed and contactor 26 is open; as soon as the double-pole switch 9 is closed the cathode filamentary electrodes 4a, 4b, and 4c are heated, the rotary switch 12 produces voltage impulses at point 15, and coil 25 of time-delay relay 16 is energized. After one or several seconds, the time-delay relay 16 closes its

contactor 26, as a result of which voltage impulses are imparted to the auxiliary electrodes 14a, 14b, and 14c so that all the lamps are ignited. The discharge current flowing through coil 21 of relay 22 causes the opening of contactor 24 and thus eliminates the heating of the cathode filaments.

Fig. 2 represents by way of example a diagram of connections of discharge lamps for the particular case of a railroad car without compartments and comprising six groups of lamp circuits, each group having seven lamps all subjected to the traction voltage of 700 volts and connected in series, each lamp being 0.60 meter long and absorbing 0.35 ampere. The circuit comprises also a 72 volt auxiliary battery 31.

Thus, Fig. 2 represents a wiring diagram of several groups of series-connected lamps, the groups themselves being connected in multiple so that if one lamp of a group should become defective only a fraction of the lamps in the total group will be extinguished. In addition, switching means are provided to shunt out or short-circuit a defective lamp and re-ignite the remaining lamps of that particular group in a new series combination. The corresponding elements which Fig. 2 has in common with Fig. 1 have the same reference numerals.

A converter 32, energized by the storage battery 31, constitutes the alternating current source of supply 20, 20'. A manual make-and-break switch 33 controls the energization of converter 32. A time-delay relay or switching means 34 comprising a coil 35 energized by the storage battery 31 controls a contactor 36 which in turn is in series with the direct current supply 1, 1'. In addition, I provide another time-delay relay or switching means 37 comprising a coil 38, connected across the direct current terminals of the converter 32, and a contactor 39 connected to point 15 in the starting circuit 10, 10' and a common wire associated with the auxiliary electrodes 14a, 14b, and 14c. The closure of contactor 39, actuated by coil 38, energizes the auxiliary electrodes 14a, 14b, 14c. A plurality of double-pole contactors or switches 40a, 40b, and 40c, etc., associated with devices 1a, 1b, 1c etc., may be used for checking the functioning of each respective device. One contactor of each of switches 40a, 40b, and 40c is connected across battery 31 through coil 38, which in turn controls the energization of the auxiliary electrodes associated with each device, and the other contactor of the above-mentioned switches shunts or short-circuits its respective device. Thus, on the one hand these double-pole switches permit short-circuiting the corresponding lamp associated therewith and, on the other hand, make it possible to bring into action the general re-starting system described herebelow.

By joining together through one single wire 41 the wires which interconnect the fourth and fifth lamps (1d and 1e or 1l and 1m) of a series, the number of lamps that go out, should one lamp in a series become inoperative, will no longer be the total sum of the series, for example 7 lamps, but will be reduced to a smaller number depending on where this common wire is placed. In Fig. 2, the number of inoperative lamps would be either three or four, depending in which group of lamps the defective lamp existed.

The circuit illustrated in Fig. 2 operates as follows: In the rest position, with contactors 36 and 39 open and contactor 24 closed, coil 35 of relay 34 becomes energized upon closure of switch 33. The energization of coil 35 closes

contactor 36 and applies a voltage across the lamps in the series parallel circuits. In addition, upon closure of switch 33 converter 32 starts, cathode thermionic filamentary electrodes 3a, 3b, 3c etc. are heated, rotary switching means 12 sets up voltage impulses at the point 15, and the coil 38 of the time-delay relay 37 is energized. After one or several seconds this time-delay relay or switching means 37 functions and closes its contactor 39, which in turn imparts voltage impulses to the auxiliary electrodes 14a, 14b, 14c etc. and effectuates the lighting of all lamps. The discharge current of the lamp groups which flows through coil 21 of relay or switching means 22 brings about the opening of contactor 24, thus interrupting the heating of the cathode filamentary electrodes of devices 1a, 1b, 1c, etc.

When it is desired to locate a lamp which no longer operates, i. e., in a series of three or four extinguished lamps, closure of the double-pole switch, such as switch 40a, corresponding to lamp 1a for a moment will indicate by a discharge occurring or not occurring in the remainder of the original series of lamps whether or not the particular lamp 1a is defective. In this manner, if the defective lamp is lamp 1a it will be bypassed and all the other lamps of the series will ignite. If a discharge does not occur in the remaining portion of the series, the procedure must be repeated successively for each one of the lamps until the defective lamp is located.

While certain specific embodiments have been shown and described, it will, of course, be understood that various modifications may be made without departing from the invention. The appended claims are, therefore, intended to cover any such modifications falling within the true spirit and scope of the invention.

What I claim as new and desire to secure by Letters Patent of the United States is:

1. Apparatus for operating a plurality of gaseous luminous electric discharge devices, of the type including a main thermionic electrode and a cooperating main electrode, comprising: a principal source of unidirectional voltage and an auxiliary source of alternating voltage, and a ballast resistance; a transformer having a primary winding connected to said auxiliary source and a plurality of secondary windings connected to said thermionic electrodes; a main discharge circuit including said devices connected in series, the thermionic electrode of one being connected to the cooperating electrode of another in sequence, the two remaining main electrodes being connected, in series with said ballast resistance, across said principal source; a starting circuit comprising a limiting resistance, continuously operative switching means for making and breaking said starting circuit, and an inductance serially connected across said unidirectional source; and an auxiliary starting electrode for each of said devices connected to the inductive side of said switching means.

2. Apparatus for operating a plurality of gaseous luminous electric discharge devices, of the type including a main filamentary electrode, a cooperating main electrode, and an auxiliary starting electrode located intermediate the ends thereof, comprising: a principal source of unidi-

rectional voltage, an auxiliary source of alternating voltage, and a ballast resistance; a transformer having a primary winding connected to said auxiliary source and a plurality of secondary windings connected to said filamentary electrodes; a main discharge circuit including said devices connected in series, the filamentary electrode of one being connected to the cooperating electrode of another in sequence, the two remaining main electrodes being connected, in series with said ballast resistance, across said principal source; a starting circuit comprising a limiting resistance, continuously operating switching means for making and breaking said starting circuit, and an inductance serially connected across said unidirectional source; and connections from said auxiliary electrodes to the inductive side of said switching means.

3. Apparatus for operating a plurality of gaseous luminous electric discharge devices, of the type including a main thermionic electrode and a cooperating main electrode, comprising: a principal source of unidirectional voltage, an auxiliary source of alternating voltage, and a ballast resistance; a transformer having a primary winding connected to said auxiliary source and a plurality of secondary windings connected to said thermionic electrodes; a main discharge circuit including said devices connected in series, the thermionic electrode of one being connected to the cooperating electrode of another in sequence, the two remaining main electrodes being connected, in series with said ballast resistance, across said principal source; a starting circuit comprising a limiting resistance, continuously operating switching means for making and breaking said starting circuit, and an inductance serially connected across said unidirectional source; an auxiliary starting electrode for each of said devices connected to the inductive side of said switching means; and a pair of time-delay relays, the first of said relays having a normally closed contactor inserted in series with said primary winding and said auxiliary source and having an operating coil connected in series with said main discharge circuit, and the second of said relays having a normally open contactor inserted in series with said auxiliary electrodes and the inductive side of said switching means, and having an operating coil connected to said primary winding.
